JOHN E. BELL, DECEASED, LATE OF BROOKLYN, NEW YORK, BY LOLA R. BELL, EXECUTRIX, OF BROOKLYN, NEW YORK, ASSIGNOR TO FOSTER WHEELER CORPORATION, OF NEW YORK, N. Y., A CORPORATION OF NEW YORK

METHOD OF SUPERHEATING STEAM

Original application filed April 26, 1923, Serial No. 634,712. Divided and this application filed January 23, 1925. Serial No. 4,181.

The general object of the present invention is to provide an improved method of regulating the heat absorbing capacity of radiant heat absorbing apparatus. More specifically, 5 the primary object of the invention is to provide a simple and effective method of operating a superheater boiler comprising a radiant heat superheater, in such manner as to obtain a desirably uniform degree of superheat 10 under varying load conditions, notwithstanding the tendency of such a superheater boiler to give a degree of superheat which decreases with the rate at which steam is generated throughout the normal range of fluctuations 15 in said rate.

In regulating the degree of superheat obtained in accordance with the present invention, advantage is taken of the fact that furnace dust tends continually to accumulate on 20 the heat absorbing face of the radiant heat superheater, and that such accumulations reduce the heat absorbing capacity of the superheater; and the superheat obtained is regulated by providing means for removing such 25 dust accumulations in a regulable manner and by operating such dust removing means to vary the furnace dust accumulations on the superheater and thereby the heat absorbing capacity of the superheater, at different 30 times and under different conditions, as required to give the degree of superheat desired.

The various features of novelty which characterize the invention are pointed out with particularity in the claims annexed to, and 35 forming a part of this specification. For a better understanding of the invention, however, its advantages and specific objects attained with its use, reference should be had to the accompanying drawings and descriptive matter in which there is illustrated and described a preferred form of apparatus for use in carrying out the invention claimed herein.

45 Of the drawings:

Fig. 1 is an elevation in section of a portion of the wall of a combustion chamber in which a radiant heat superheater is incorporated;

50 Fig. 2 is an elevation of a portion of the inner wall of the combustion chamber shown

in Fig. 1, with parts broken away and in section;

Fig. 3 is a partial section on the line 3—3 of Fig. 2;

Fig. 4 is a longitudinal section of a portion 55 of one of the superheater elements of Figs. 1, 2, and 3; and

Fig. 5 is a section on the line 5—5 of Fig. 4.

In the apparatus shown in the drawings, A represents a boiler furnace combustion 60 chamber wall incorporating a radiant heat superheater provided with one form of soot blowing provisions suitable for use in accordance with the present invention. The superheater shown comprises a plurality of elements B which are shown as vertically disposed, though they may be horizontal. Each element B is connected at its ends by horizontal pipes C to inlet and outlet headers D and DA. Each superheater element B is 70 formed of hollow sections connected at their ends by threaded nipples or sleeves E. The joints between the section ends thus connected are advantageously sealed by welding the sections together as indicated at F. The sections, 75 as shown, are formed of cast metal, such as ordinary cast steel or more refractory steel alloys. Each of the elements B has a plane heat absorbing face exposed to the interior of the combustion chamber, and has side faces 80 perpendicular to its inner face, and in the assembled superheater, the inner faces of the various elements unite to form a substantially smooth or plane heat absorbing surface.

The superheater elements B are formed at 85 their rear sides with bosses B' for connecting the elements to suitable supports. These supports, as shown, in Figs. 1 to 3, comprise angle bars g arranged parallel to, and one immediately behind each element B. These 90 angle bars are formed with holes to receive bolts g' tapped into the bosses B'. To accommodate relative longitudinal expansion of each element B and the corresponding support g, each element may be rigidly clamped 95 adjacent its center, to its support g, by the corresponding bolt g', while the holes in that element g through which the other bolts g' pass may be longitudinally slotted. The angle bars g may, or may not be connected to, 100

and form a part of a structural metal framework G back of the superheater, which assists in carrying the weight of the masonry furnace wall above the superheater. If so connected, the angle bars *g* form means for carrying the weight of the superheater element, and when not so connected, the superheater elements may be suspended from their upper ends, or may rest at their lower ends against a suitable abutment or support. In any event, the pipes C provide the flexibility needed to accommodate the thermal expansion and contraction of the elements B relative to the external columns, or metallic framework by which the headers D and DA are supported.

In the operation of such a superheater as is shown in the drawings, soot, ashes and other furnace dust tend to continuously deposit on the heat absorbing face of the superheater, and such deposits diminish the heat absorption capacity of the superheater. To remove such deposits, when and as required, provisions are made for sweeping the deposited dust, ashes or other furnace dust from the heat absorbing face of the superheater, with jets of a suitable cleaning fluid. These provisions, as shown, comprise nozzles mounted in the superheater and protected against overheating by the transfer of heat from the metallic structure of the superheater to the steam superheated in the circulating channels thereof, and supplied with cleaning fluid through passages for the latter formed in the superheater. Each nozzle, in the particular construction shown, is formed by the closed end of a tubular member H which traverses the steam thoroughfare B' of the corresponding superheater element B, and is threaded into the latter at opposite sides of said thoroughfare. To seal the joints between each member H and the superheater element into which it is threaded, the parts are advantageously welded together as indicated at H'. The nozzle end of each member H is enlarged to form a head H² which abuts against the heat absorbing face of the superheater element proper, and in which are formed a series of angularly displaced radial discharge orifices H³, through which a suitable cleaning fluid, supplied under proper pressure to the interior of each member H, is discharged in jets parallel to, and closely adjacent to the heat absorbing surface of the superheater. The inner end of each member H may advantageously be polygonal in outline to facilitate the application of a wrench for screwing the member into and out of place. To provide sufficient flow space for the steam flowing past the members H, the superheater element thoroughfares B' may advantageously be enlarged, as indicated at B³ adjacent each member H.

The various members H are so disposed

70 the entire heat absorbing face of the superheater. As shown in Figs. 1 to 4, the members H are arranged in transverse rows spaced a couple of feet or so apart, a portion only of the various superheater elements B having members H mounted in them. The means shown for supplying cleaning fluid to the members H comprises supply piping I connected to each of the members H and including a common branch supply pipe I' for 75 each member H in each horizontal row of such members. Each pipe I' is connected by an individual control valve I² to a cleaning fluid supply main I³. The cleaning fluid supplied to the main I³ may well be superheated steam, though other cleaning fluids supplied under suitable pressure may be employed.

80 With the cleaning provisions described, the heat absorbing face of the superheater 85 can be kept as free as may be desired of deposited soot, ashes or other furnace dust. The cleaning fluid may be supplied intermittently or constantly to the members H. When supplied intermittently, the sections of 90 the superheater at different levels may be successively cleaned, each section being swept with the proper amount of cleaning fluid. While I contemplate supplying cleaning fluid to the nozzles intermittently in ordinary 95 practice, it may sometimes be desirable to supply cleaning fluid continuously and this is possible as the cleaning fluid jets discharged over the heat absorbing surface do not materially affect the absorption of 100 radiant heat by said surface. Whether the cleaning fluid is supplied intermittently or continuously, the independent control of the amount of cleaning fluid supplied for cleaning different sections of the superheater 105 facilitates the regulation of the heat absorbing capacity of the superheater which diminishes rapidly as the accumulation of furnace dust on its heat absorbing surface increases.

110 In accordance with the present invention, the superheating effect obtained is regulated by operating the soot blowing provisions in such fashion as to maintain a minimum average thickness of deposit when a high superheating effect is desired, and to maintain a deposit of greater average thickness when a lesser superheating effect is desired. For instance, in the normal operation of a superheater boiler having a radiant heat superheater there is a tendency for the degree of superheat to decrease as the rate at which steam is generated increases. When the rate at which steam is generated varies more or less gradually and uniformly during various periods in each day, as is the case in most large central power stations, it is possible to obtain an approximately constant superheat by keeping the heat absorbing face of the entire superheater, or portions thereof, comparative- 120 125 130

ly clean during heavy boiler load periods, and allowing dust deposits to remain on said face or portions thereof, during periods in which the load is lighter. The soot blowing provisions may also be operated without regard to the degree to permit dust deposits to accumulate and protect the superheater against overheating during very light and no load periods in which the superheater elements might otherwise become overheated.

With the described provisions for separately cleaning different sections of the heat absorbing surface of the superheater it is possible to readily regulate the heat absorbing capacity of the apparatus in many cases, without paying close attention to the thickness of the character of deposit on any particular section of said face, by successively cleaning different sections both with respect to the frequency of the cleaning operations and with respect to the extent or number of sections cleaned, and the degree of cleaning, as required to maintain the desired heat absorbing effect. For example, in the case of a superheater boiler operating under fairly steady load conditions, the frequency with which successive sections of the superheater are cleaned may well be made dependent upon the reading of the thermometer showing the superheat obtained,—the cleaning provisions being operated whenever the degree of superheat begins to fall off, and being then operated to the extent necessary to restore the superheat to its desired value.

While the invention was primarily devised for, and is especially adapted for use in controlling the superheating effect obtained with a radiant heat superheater, the invention may be used, of course, with other forms of radiant heat absorbing apparatus in which a regulated heat absorbing effect is desirable. The novel soot blowing provisions disclosed, but not claimed herein, are claimed in the prior application, Serial No. 634,712, filed April 26, 1923, of which this application is a division.

Having now described the invention, what is claimed as new and described to be secured by Letters Patent, is:

1. The method of operating fluid heating apparatus comprising a metallic structure having one face exposed to the interior of a furnace chamber and channels parallel to said face for the fluid to be heated, which consists in regulating the accumulation of furnace dust on said face to thereby vary the heat absorption capacity of said face.

2. The method of operating a radiant heat superheater which consists in cleaning the heat absorbing surface of the superheater in accordance with variations in the superheater load, so as to make the heat absorption capacity of the superheater relatively higher at heavy loads than at low loads.

3. The method of operating fluid heating apparatus having a surface absorbing heat by

radiation which consists in successively removing furnace dust from different sections of said surface when and as required to maintain a desired rate of heat absorption, which is normally less than the maximum rate of heat absorption.

4. The method of operating a radiant heat superheater which consists in removing furnace dust accumulations from different sections of the radiant heat absorbing face of the superheater in accordance with changes in the degree of superheat from a desired degree of superheat.

5. In the art of operating a boiler furnace having an enclosing wall including a metallic fluid conduit structure having one face exposed to the interior of the furnace chamber and absorbing radiant heat therefrom and on which furnace ashes normally accumulate, the method of regulating the rate of heat absorption of said fluid conduit structure which comprises allowing a greater accumulation of furnace ashes on said face at light loads than at heavy loads.

6. In the art of operating a steam boiler burning fuel in a furnace chamber having an enclosing wall including a fluid cooled wall surface exposed to heat radiation from the combustion chamber and on which furnace dust tends to accumulate, the method of regulating the rate of heat absorption of said surface which comprises removing the dust from one portion of said surface while permitting dust to accumulate on another portion of said surface.

Signed in the county of New York and State of New York, this 20th day of January, A. D. 1925.
